UNITED STATES PATENT OFFICE

WILLIAM KLOCKE, OF WOODHAVEN, NEW YORK, ASSIGNOR TO E. W. BLISS COMPANY,
OF BROOKLYN, NEW YORK, A CORPORATION OF DELAWARE

POWER PRESS

Application filed June 2, 1927. Serial No. 195,976.

This invention relates to power driven presses for punching, stamping, corrugating, or otherwise working metal in sheet or plate form or for the production of drop forgings.

5 According to the present invention the working parts of two presses are mounted upon one press frame. Ordinarily the frame supports the working parts peculiar to only one press and for two presses two complete frames are required. By the present invention the usual idle or unutilized back portion of a press frame is made to carry a second set of working parts, so that the press becomes a double press equivalent to two 15 presses set back to back but taking less room because only one frame serves for both. In the use of presses of this character it rarely happens that a press is used continuously so that there are considerable intervals of 20 time when any given press is idle; such idle presses occupy valuable space which during such time is unutilized. The present invention where a number of presses are employed effects a considerable saving in the first cost, 25 since the single frame for the twin presses has but little more weight than the usual frame for one press; it effects a considerable saving in room, so that floor space is better utilized and correspondingly avoids the loss 30 of space when presses are idle; and is safer because it avoids passages behind presses where accidents are more liable to happen. When two presses are running, it would rarely happen that their punches or other striking parts would encounter the resistance in 35 their effective strokes at the same instant, and only in such event could the press frame receive the maximum strain upon it incident to the operation of both presses; to save the 40 press from such strain and thereby enable the frame for the two presses to be made substantially no heavier than the ordinary frame for one press, the present invention provides means whereby to guard against the simultaneous starting of both presses and consequently to prevent their both receiving their active strains at the same instant.

The preferred form of the invention is shown in the accompanying drawings, where-
in,—

Figure 1 is a side elevation of the double or twin press.

Fig. 2 is a front elevation of one side of the press viewed from the right in Fig. 1.

Fig. 3 is a plan of the press.

Fig. 4 is a side elevation of the press frame, showing it partly in section, this view being on a smaller scale.

Fig. 5 is a fragmentary horizontal view on the line 5—5 in Fig. 1.

Referring to the drawings, the single or unitary press frame for the two working units constituting essentially two presses is lettered A. This frame is formed on one side with press parts lettered collectively B, 65 and on the other side with press parts lettered collectively C. These might be identical, but are shown as different types of presses, the press B having a removable horn a and an adjustable bed b with a lifting screw c and fastening bolts d engaging in slots E for fixing the bed at varying heights. The press parts C comprise as shown a fixed or immovable bed f carried on a solid bracket g in the usual manner. Both the presses have 70 any usual construction of vertically reciprocating head or slide h carried in slideways in any usual manner and connected in any suitable way with the operating means whereby to reciprocate these heads. The drawings 75 show drive shafts D and D' driven by pulleys or fly wheels E and E', the shafts having cranks or eccentrics connected by connecting rods or pitmen i to the respective sliding heads h, these being usual constructions in such presses, and forming no part of the present invention. They may be substituted by any other known type of driving means for power presses. In short the particular press mechanisms shown are given 80 merely as examples.

In order to provide bearings for the two shafts D D', the frame A at its top is carried to both sides and there formed with bearing members j j'. The frame forms in effect a 95 bridge across between these bearings in order that in the event of concurrent or nearly concurrent working strains being encountered in the two press members, the horizontal components of these strains may be resisted di- 100

rectly or substantially so by the solid metal of the presshead extending almost directly across between the bearings. This also strengthens the head of the frame for resisting the strain due to the operation of either press alone; and if both strains concur, the frame is subjected to no more or but little more stress than if it supported but a single set of press members.

10 It is important to insure against the frame receiving simultaneously the reaction due to the punching or other work strains of the two sets of press members occurring at precisely the same instant, that is, at the same point in the revolution of each of the two shafts. To this end provision is made for insuring that the two presses may not happen to be started exactly together. To accomplish this, advantage is taken of the construction 15 of clutch which is universally applied in presses of the Bliss type, namely, a rocking key or bolt carried in a groove in the shaft and adapted when oscillated to enter into one or more notches within the hub of the rotating pulley or other driving part E or E'. As this type of clutch is well understood, it is sufficient to illustrate it in dotted outline, as in Fig. 1, where k is the oscillating key having a projecting arm l which is stopped by encountering a lever m operated from a treadle T or T' through intervening connecting rods. When the treadle is pressed down, the stop lever m is pulled down, thereby freeing the key which by the action of a spring (not 20 shown) oscillates so as to engage a notch in the hub and lock the driving wheel and shaft together for at least one revolution, or for as many revolutions as the treadle is kept pressed down; when the treadle is released, 25 the lever m is pressed up (by a spring not shown) again into the path of the revolving arm l which it stops, turning the key to the position where it frees itself from the notch in the driving wheel. To this well-known 30 mechanism I superadd a shaft F to which are connected arms p p' on opposite sides of the frame, the arm p forming a joint connection between the rods q r, between the treadle and clutch stop lever for one press and the 35 arm p' performing the same function with respect to the rods q' r' of the other press. The shaft F has the arm p keyed to it while the arm p' turns freely on it; it also has keyed to it an arm s which consequently 40 through the shaft forms a lever with the arm p. The arm s acts as a stop cooperating with the arm p', being preferably provided with a screw t arranged to strike a lug on the arm p'. It results from this construction that 45 when the treadle T is depressed to start the press members B, the arm s t acts as a stop to prevent the pulling down of the arm p' and consequently to prevent the depression of the treadle T' to start the press members 50 C. Or, on the other hand, if the treadle T' 55

is first depressed, its arm p' coacting with the arm s and screw t will prevent the pressing down of the treadle T to start the press B. This coacting mechanism thus serves, in the case of presses which are driven one revolution at a time to make one stroke upon the pressing down of the treadle, to prevent both presses being started at the same instant, and consequently to prevent both presses performing their working strokes at the same instant and subjecting the frame to a double strain.

60 The press provided by this invention saves considerable valuable factory space, since four rows of presses may occupy only the same room as three rows of presses of the old type.

65 There is also considerable economy in first cost and weight, since one frame serves for the working parts of two presses, and is of but slightly more weight than a frame for a single press.

70 I am aware that punching presses have been made, each with a complete frame, and the two frames have been mounted close together, back to back, and in some instances have been bolted together. Such construction effects no such saving in the weight, first cost, or space as is attained by the present invention. The depth of the press frames in such presses is twice that of a single press frame; whereas according to the present invention the press frame for the working parts of two presses is in the main of only the 75 same depth as a press frame for a single press of the same type.

80 In the specific construction the mechanisms or press members may be varied in any of the ways customary in the art. The invention is thus susceptible of modification within the 85 scope of the appended claims.

90 I claim as my invention:

95 1. A twin press having a single frame and the press members of two presses carried thereby, and means for preventing the simultaneous starting of both presses.

100 2. A twin press according to claim 1, such means comprising movable stop mechanism inter-connecting the starting means of both presses, whereby when either starting means is displaced to start the press, it blocks the starting movement of the other starting means.

105 In witness whereof, I have hereunto signed my name.

110 WILLIAM KLOCHE.
